UNITED STATES PATENT OFFICE.

ADOLPH HERPOLSHEIMER, OF SEWARD, NEBRASKA.

TRAIN-PIPE COUPLING.

SPECIFICATION forming part of Letters Patent No. 738,904, dated September 15, 1903.

Application filed December 22, 1902. Serial No. 136,250. (No model.)

To all whom it may concern:

Be it known that I, ADOLPH HERPOLSHEIMER, a citizen of the United States, residing at Seward, in the county of Seward and State of Nebraska, have invented a new and useful Train-Pipe Coupling, of which the following is a specification.

My invention relates to car-couplers, and has for its objects to produce a device of this character which will be simple of construction, inexpensive to manufacture and apply to any cars, efficient in operation, and which will automatically couple and uncouple both the cars and the train-pipe.

15 To these ends the invention comprises, in a train-pipe coupler, the combination, with a sliding member, of a spring tending to project said member outward, a coöperating member adapted to force said member inward 20 against the action of the spring, and a rotatable valve adapted to be opened when said member is moved inward and to be closed when moved outward.

The invention further comprises the details of construction and combination of parts more fully hereinafter described.

In the accompanying drawings, Figure 1 is a side elevation illustrating two cars coupled by my improved device. Fig. 2 is a similar 30 view of the coupler on an enlarged scale. Fig. 3 is a horizontal sectional plan illustrating the internal mechanism of the coupler. Fig. 4 is a horizontal sectional elevation through the head of the train-pipe-coupling 35 member to show the valve and its operating means.

Referring to the drawings, 1 and 2 indicate two members of the coupler attached each to the adjacent or meeting end of two cars in 40 the usual or any desired manner to couple or uncouple the same, as in Fig. 1. As the construction and operation of the two members of the coupler are identical in every particular except the change in position of the parts 45 whereby they coöperate, I will describe in detail but one member, in which—

3 indicates the shank of the coupler, provided with a head 4, recessed as usual, as at 5.

50 6 is a movable jaw pivoted in the head on

vertical axis 7, upon which it is adapted to swing freely to couple or uncouple the cars, as presently explained. The jaw is provided with an integral finger 8, which lies normally within a socket 9, formed in the interior of 55 the head to receive the same and the jaw-operating mechanism.

10 is a horizontal lever mounted on the top face of the coupler-head and extending outward to the side of the car in position to 60 be readily operated by the attendant without his having to pass between the cars. This lever may, through suitable connections, be operated from the top of the car, if so desired. The lever 10 is mounted upon the 65 end of a vertical pivot 11, journaled in the coupler-head. Fixed near the lower end of the pivot within the socket 9 and adapted to be operated thereby is a radially-swinging finger 12, carrying a pivoted link 13, formed 70 at its free end with a recess 14, adapted to engage the finger 8 of the jaw for the purpose hereinafter pointed out.

15 indicates the train-pipe-coupling member in the form of a rod 16, adapted to slide 75 in suitable bearings 17 and 18 in the form of lugs depending vertically from the under side of the car-coupler. The rod 16 carries a coupling-head 19, recessed at 20 to form a horizontal projecting portion or arm 21. 80

22 is a rotatable horizontal valve mounted in the arm 21, the end of the valve being flush with the inner face of the said arm and its outer end being fixedly attached to a crank-arm 23, by which the valve is rotated, 85 as presently described. The valve is provided with a central horizontal air-passage 24, open at its outer end, or that end which registers with the valve in the coöperating pipe-coupling member, but closed at its inner end.

25 is an air-passage formed through the wall of the valve and adapted to establish communication between the passage 24 and a passage formed through the nipple 26, to 95 which the end of the train-pipe is attached.

27 is a tongue or key formed on the inner face of the valve, by which it is locked to the valve carried by the coöperating member.

28 is a rigid horizontally-projecting arm 100

secured at one end to the lug 17 and having the crank-arm 23 pivoted to its other end, as at 28^a.

29 is a spring which is mounted on the rod 5 16 with one end bearing against the lug 18 and its other end against a shoulder 30, formed on the rod. This spring tends normally to project the member forward when uncoupled.

31 is a stop which abuts against the lug 17 to limit the forward projection of the rod.

32 is a set-screw by which the valve 22 may be tightened in its seat, and 33 is a bearing for the set-screw.

15 In coupling two cars the following action takes place: Supposing the movable jaw 6 to occupy the position shown in dotted lines in Fig. 3, the cars coming together will automatically throw the jaw inward, causing its 20 finger 8 to engage the recess 14 in link 13, moving the same to the position shown in full lines, thus locking the parts. At the same time the member 15 of the train-pipe coupler will be automatically forced inward 25 by the coacting member on the adjacent car against the action of spring 39, thus causing the crank-arm 23 to rock on its pivot 28^a and rotate the valve 22. This rotation of the valve brings the air-passage 25 in the wall of 30 the valve into register with the air-passage in the nipple 26 and at the same time locks the valve to the valve in the coöperating members and establishes communication with the pipe-section carried thereby. To uncouple, 35 it is only necessary for the brakeman to move lever 10 to release the finger 8 of the jaw 6 and permit the cars to separate, this separation of the cars allowing the spring to

move the pipe-coupling member outward and operate the valve in a manner reversely to that above described.

It is to be understood that I do not limit or confine myself to the details herein shown and described, as such changes therein as would suggest themselves to the skilled mechanic may be made without departing from the spirit or scope of my invention.

Having thus described my invention, what I claim is—

1. In a train-pipe coupler, the combination 50 with a sliding member of a spring tending to project said member outward, a coöperating member adapted to force said member inward against the action of the spring and a rotatable valve adapted to be opened when 55 said member is moved inward and to be closed when moved outward.

2. In a train-pipe coupler, the combination with a sliding member of a spring tending to project said member outward, a coöperating 60 member adapted to force said member inward against the action of the spring, a rotatable valve carried by said member, and a crank-arm pivotally connected to the coupler, and adapted to move the valve to open position 65 when the member is forced inward and to close the valve when the member is moved outward.

In testimony that I claim the foregoing as my own I have hereto affixed my signature in the presence of two witnesses.

ADOLPH HERPOLSHEIMER.
